UNITED STATES PATENT OFFICE

2,100,711

CONTAINER

Ronald I. Drake, Appleton, Wis., assignor to Beatrice Creamery Company, Chicago, Ill., a corporation of Delaware

Application June 14, 1933, Serial No. 675,755

10 Claims. (Cl. 229—23)

The invention relates to improvements in the type of container made of paper or analogous fibrous sheet material adapted for containing various forms of food products and particularly 5 dairy products as ice cream and the like of a liquid or semi-solid character and particularly containers of the type as shown in the United States patent of Kenneth L. Murray, 2,042,796 of June 2, 1936, the same being containers of the 10 two-piece type in which the contents of the package are enclosed by an inner closure member of creasable and preferably waterproof paperboard or sheet material of a fibrous character of a frusto-pyramidal form adapted to be 15 enclosed upon its longitudinal sides by an open-ended tube-like cover portion of a corresponding form to closely surround the side and end walls of the four longitudinal walls of the folded inner container blank, the two elements of the complete 20 container being of a knock-down character, so that the sheet materials of the blanks may be transported in a flat condition if desired and easily assembled without the employment of any tools or pasting materials by a simple hand folding operation.

The primary object of my invention is to improve the construction of and mode of assembling and securing together the free ends of the outer container member to securely lock the extremities 30 thereof together without the necessity of any pasting or gluing operation which is difficult and expensive, particularly where the paper sheets or fiberboards of which the material is formed has been treated to render the same of a waterproof character since mucilaginous materials do 35 not readily adhere to such treated paper surfaces.

Other objects of the invention will appear from the following description of the preferred form 40 of my invention as contained in the following specification, reference being had to the drawing forming a part thereof, the novel features of the invention being set forth in the appended claims.

In the said drawing:

Fig. 1 is a perspective view of a two piece container, the outer tube-like enveloping portion of which embodies the invention.

Fig. 2 is a transverse, median, vertical, sectional view through the assembled tube-like outer covering of the container, the section being taken 50 as indicated on line 2—2 of Fig. 3 looking in the direction indicated by the arrows, Fig. 3 being a section on line 3—3 of Fig. 2 looking downwardly as indicated by the arrows.

Figs. 4 and 5 are fragmentary views of the 55 specially constructed interlocking device con-

structed integrally with the body of the blank of which the same is formed, Fig. 4 illustrating the manner of initially placing the interlocking devices into co-operative relation, and Fig. 5 showing the completed locked joint.

Fig. 6 is a view similar to Fig. 5 showing the reverse side of the co-operating parts of the interlocking joint.

Fig. 7 is a detail, sectional view on line 7—7 of Fig. 5 looking in the direction indicated by the 10 arrows.

Fig. 8 is a plan view of the complete blank forming the outer tube-like portion of the container, and illustrating the manner of cutting and slitting the periphery and body portions of the blank and scoring the same for folding and locking in its set up condition for assembly with the companion container member, in the manner illustrated in Fig. 1.

In the drawing the reference character 10 designates the inner foldable portion of the container, preferably in the form of a frustum of a pyramid in order to secure the most perfect co-operating relation between the latter and its outer tube-like container or shell, which is designated generally by the reference character 11, applied to the same including the blank of Fig. 8 as well as the set up shell shown in Fig. 1. The blank 11 is made up of the side sections 12 and 13 and the integral connecting end member 14, these portions being bounded by suitable scored lines 15 and 16 and 17 and 18 respectively where the paper body may be creased or indented preferably in a series of short broken creases for folding the material of the body to the substantially right angular positions on 15 and 16 and also for folding the sheet extensions beyond the creased lines 17 and 18 producing the flaps or extensions 19 and 20 designed to overlap each other when assembled in the manner illustrated in Figs. 1 to 30 6 inclusive, the section or flap 19 overlying the part 20 in the manner illustrated in common to containers of this general character. The section 20 will preferably be of approximately the width of the section 14 allowing merely for thickness of the material as the sections are folded around each other in the overlapping positions and it will be seen that when the member 11 is brought to the tubular form, the section 19 will 35 overlie the section 20 so that the specially formed integral locking members 21 on the section 19 may be caused to enter the slotted openings formed by producing the depressible tongues 22, the latter each being preferably formed by the co-operation and intersection of two elongated 40 45 50 55

55

kerfs or slits 23, 24. The slits 23 extend preferably longitudinally of the section 20 at the predetermined position to insure the proper interlocked and overlapping positions of the sections 5 19 and 20, their location obviously depending upon the width of the overlapping section 19 and the position of the interlocking projections 21 thereon. The longitudinally extending slits 23 are intersected by the slits 24 which have their 10 terminals curved as indicated at 25.

It will be apparent that the device to be operative for the insertion of the interlocking projections 21 with the intersecting slits 24 which partially bound the depressible tongues 22 in order 15 that the interlocking projections 21 may be readily inserted in the slotted section 20 the additional slits or kerfs 24, 25 are provided freeing the body of the tongues 22 at one end so that they may flex inwardly to bring the interlocking parts 20 easily and surely into their proper interlocking relations.

Another important feature of the invention to secure facility and ease of operation resides in the construction of the interlocking or hooked 25 projections 21 by which their outer peripheries are curved from the bases of each outwardly and around so that they have overlying projecting ends as indicated at 26 with locking recesses 27 opening downwardly for co-operating with the 30 lower extremities of the slits or kerfs 23 in forming the requisite interlocking in the manner shown most clearly in Figs. 4 to 6 inclusive in the operation of the improved container as the inner body portion has been folded to its set-up 35 condition with the top closure flaps as shown in Fig. 1 in the folded position or closed position as may be desired.

The outer tubular portion embodying the improved interlocking mechanism of my invention 40 may be assembled by folding the same to the tubular formation with the terminal section 19 overlying the opposite terminal section 20. This will put the locking projections 21 in position adjacent the depressible tongues 22 with their 45 bounding slits 23 and 24, 25 and the described shapes and relations of the projections 21 and the tongues 22 are such that when the curved forward edges of the projections 21 are pressed toward and upon the tongues 22, they will be inwardly depressed, thus more readily opening up 50 the slits 23 to the ingress of the rounded body portions of the projections 21. It will be noted that the projections 21 on the sides thereof opposite the underlying slots 27 at their bases are 55 curved as indicated at 28 and that such curved portions 28 will contact with the curved extremities 25 of the slits 24 and being angular upon the first movement of their insertion, the sections 19 and 20 will be in the approximate 60 positions of the fragmentary portions of such sections as indicated in Fig. 4. As soon as the curved body portions of the projections 21 have passed through the slits or kerfs 23 to cause the undercut slots 27 of the projections to coincide 65 with the slits or kerfs 23 as shown in Fig. 4, further ingress of the projections 21 due to the contact of the angular portions 28 with the upper ends of the slits or kerfs 23 will tend to cause 70 the body of the projection 21 as well as the body of the section 19 to move downwardly in relation to the section 20 so that the projecting lower extremities of the members 21 will overlie the terminal portions of the slits 23 to produce an interlock which will be effective to securely hold 75 the sections 19 and 20 in their permanent over-

lapping relation, when the folded or set up inner portion of the container 10 may be inserted and securely held therein for filling of the container and for transportation and distribution.

In operation the formation of the outer tube-like shell 11 by inserting the projections 21 into the slits 23 as represented in Figures 4 and 5, will cause the resilient tongue 22 to extend inwardly as shown more clearly in Fig. 2. The insertion of the inner container 10 within the outer shell 11 5 either when the inner container is filled with material or when it is empty, will cause the projecting tips of the tongues 22 to be depressed or returned to the space from which they came. This is made possible by the downward movement 10 of the projections 26 being hooked in place at the bottom of the slot 23 and because the tongues 22 are longer than the width of the neck of the hooked portion 27 as clearly shown in Figs. 6 and 7. Thus the extremities of the spring tongues 20 22 are forced outwardly by the inner container 11 so that these extremities re-engage in the slot of the wall from which they are formed and effectively interlock the projections 26 in place. If the inner container is filled with any material 25 the tendency of the weight of the material itself is to press the upper tips of the tongues 22 more firmly into such interlocking engagement and thus to more effectually lock the outer container 11 in position.

As set forth in the description of this type of container in the before described patent of Kenneth L. Murray, after the inner container is inserted in the outer tubular portion embodying my invention, this type of outer holder for the inner portion of the container will permit the upward movement of the inner part of the container in relation to the holder because of the downwardly tapering shape of the parts so that when desired the outer holder may be easily removed by a relatively downward telescopic movement thus making it unnecessary as a matter of general practice to unlock the overlapping portions 19 and 20 of the outer and tubular part of the container embodying the invention.

From the foregoing description of my invention it will be seen that I have provided an improved construction of an interlocking joint for tubular paper containers that is operable without the use 40 of any adhesive or extraneous attaching materials 50 or tools, the construction of which permits of the assembly of the parts of the tubular container members in a facile manner by comparatively unskilled help by employing a simple hand operation, and the interlocking parts being integrally 55 formed in the body of the sheet of the tubular container, lend themselves readily to practical production and operation in the use of waterproofed and other materials that are difficult of attachment by most common forms of mucilaginous adhesive substances.

In order that the invention might be understood the details of the preferred embodiment thereof are set forth but it is not desired to be limited to such details of construction except as 60 set forth in the claims.

I claim:

1. A two-piece container comprising an inner body portion in the form of a frustum of a pyramid and an outer co-operating portion comprising a sheet of flexible material adapted to be given a tubular form for telescopically receiving the inner frusto-pyramidal body portion, said outer portion being adapted to be secured in the tubu- 70 75 75

lar form by the provision of two-overlapping terminal portions, one of which terminal portions is provided with a plurality of spaced-apart projections on its marginal edge and the other portion having a plurality of correspondingly spaced 5 depressible tongues formed integrally from the body thereof, each of said deppressible tongues being formed by an elongated kerf and by a second kerf extending for the major portion of 10 its length approximately parallel to the first said kerf and being thence curved to intersect the first said kerf whereby to free one end of the said deppressible tongues from the body of the material so that the tongue is free to flex at one 15 end for the full length of the kerfs, the said spaced-apart projections each being convexly curved on one side to co-operate with the said curved intersecting kerf at the free end of the tongues and each of the said projections on its 20 underside being undercut adjacent the point of its integral connection with the marginal edge of the body portion of the sheet whereby to provide interlocking engagement of the respective projections with the material of the body portion of 25 the sheet at the terminal of the kerf adjacent the base of each of said tongues when the terminal portions of the sheet are brought into overlapping engagement by the insertion of the spaced-apart projections through the respective openings in 30 the sheet bounded by the kerfs forming the tongues and the terminal portions of the sheet are laterally shifted to bring the undercut portions of the projections into interlocking relationship with the tongue kerfs at the bases of 35 the respective tongues in the manner described and the free end of each tongue being pressed outwardly by the inserted inner body portion to engage the convexly curved portion of the correspondingly inserted projection.

40 2. An improved construction for uniting the terminal portions of flexible sheet materials in overlapping relation with each other, comprising a sheet having a plurality of spaced-apart elongated kerfs forming tongues extending the full length of said kerfs in the body of one terminal portion and corresponding co-operating projections on the marginal edge of the other terminal portion, such projections being of a width adapting the same to be inserted within the space 45 normally occupied by the tongue and formed by said elongated kerfs of the first said terminal portion, there being curved cam portions at the top and undercut slots in the bases of the respective projections to permit synchronous, relative, longitudinal shifting of the said terminal portions when the said projections and slits are 50 in co-operative relation to bring the terminal portions into interlocking relation with each other and the tongues being free at one end and of a length to overlap and engage the cam portions 55 when the projections are moved to the opposite ends of the kerfs.

3. In a container, the combination with an inner body portion, of an outer portion comprising a sheet of flexible material adapted to be given a tubular form by overlapping the terminal portions thereof, there being elongated kerfs in the body of one terminal portion forming a tongue extending the full length of the kerfs and connected at one end only, and a co-operating projection formed on the lateral edge of the other terminal portion, such projection having a curved periphery at one side and provided with an undercut slot at the opposite base portions thereof to cause relative longitudinal shifting of the

said terminal portions in bringing the said terminal portions into co-incidental relation by inserting the projection against the tongue to deflect it and thence to the opening formed by the kerfs at the sides of the tongue and for locking said portions together in relation to each other and the tongue being pressed outwardly by the inner body portion so that its free extremity extends across and interlocks against the curved periphery of the inserted projection and into the end of its kerfs. 5

4. An improved construction for uniting the terminal portions of flexible sheet material in overlapping relation, comprising a plurality of spaced-apart projections on the overlapping edge 15 of one of the terminal portions and a like number of spaced-apart, registering, deppressible tongues extending transversely of the projections and formed in the other terminal portion by intersecting slits or kerfs of substantially the same 20 lengths, the said co-operating projections being provided with undercut slots at the bases thereof adapting them for hooking into interlocking relationship with the material of the terminal portions carrying the said tongues at the respective bases of said tongues therein and the end of the tongues being re-engageable with ends of their kerfs after the projections are inserted through the kerfs and moved to the opposite ends 25 thereof. 30

5. A tubular body member formed of creasable flexible material adapted to form an outer opened body portion for a container structure provided with a plurality of integrally formed projections each of which are undercut on corresponding sides at their respective bases and spaced upon the marginal edge of one of the terminal portions, there being co-operating kerfs in the body of the other terminal portion of the sheet with intersecting kerfs to form tongues integral with the sheet extending transversely of the projections, the free ends of which tongues are movable from one end of their kerfs out of the plane of the body portion of the sheet whereby to receive and co-operate with the said projections 40 when the terminal portions of the sheet are given relative lateral movement with respect to each other to form an interlocking joint, and means on the projections engaging the kerfs to give said lateral movement, the free end of each tongue 45 being returnable to re-engage in the end of its kerfs after the projection is inserted therein and moved to the opposite end of the kerfs. 50

6. As an article of manufacture, a blank cut with four trapezoidal sides to form an outer tubular portion of a two-part paper container in the form of an inverted frustum of a pyramid, comprising a creasable, flexible sheet provided with terminal portions adapted for overlapping, said sheet having a plurality of integrally 55 formed, laterally overhanging projections on the marginal edge of one of the terminal portions and a plurality of co-operating tongues extending transversely of the projections and bounded by intersecting kerfs formed in the body of the 60 other terminal portion adapted to be engaged by said laterally overhanging projections with the terminal portions of the sheet out of alignment and to form an interlocking relation between the said terminal portions when the said projections 65 are inserted in the said slots and the respective terminal portions of the blank are laterally shifted in relation to each other and the tongues being of greater lengths than the engaged portions of the projections so that they extend across the 70 75

inserted projections and the extremities of the tongues re-engage in their kerfs when pressed outwardly.

7. As an article of manufacture, an elongated sheet of flexible, creasable material provided on one of its marginal terminals with a plurality of spaced-apart integral hook-like projections and within the body portion thereof at the other extremity of the sheet, a plurality of similarly spaced, co-operable, integrally formed, flexible tongues each extending transversely of its corresponding projection and partially severed from the body of the sheet by a plurality of intersecting kerfs, the kerfs forming slots of greater length than the width of the neck of the projections at the positions where they are inserted to hook into interlocking engagement with the ends of the slots and the ends of the tongues being movable in the slots and into re-engagement with the adjacent ends of their own slots for interlocking engagement with said projections.

8. A container wrapper comprising a sheet of flexible material having projections at one end each having a rounded camming portion at one side and an undercut hook at the other side, the other end of the sheet having corresponding slits forming tongues extending the full length of the slits and the slits forming openings adapted to receive the projections of the other end of the sheet with the extremities of the sheet out of alignment, the camming portions of the projections moving the ends of the sheet into alignment as the projections are inserted in the openings formed by the slits and engaging the hooks in the ends of the slits the tongues being longer than the transverse portions of the projections engaged in the openings formed by the slits and movable into engagement with the ends of their

own openings by engagement of a container inserted in the wrapper.

9. A wrapper type of container formed of a sheet of flexible material having hooked projections at one end with rounded camming surfaces opposite the hooks and with slits at the other end of the sheet material into which the projections are inserted with the ends of the sheet out of alignment, the insertion of the projections causing the cam portions to engage the slits as they are inserted and aligning the ends of the sheet with the hooks interlocked with the ends of the slits, the necks of the projections in interlocked engagement being less in width than the length of the slits, and locking tongues formed at one side and extending the full length of the slits and each having a pointed extremity which tends to return by the engagement of a container inserted in the wrapper to the plane of the material when displaced by the insertion of the camming projections, thereby tending to interlock the projections and tongues.

10. A two-piece container comprising an inner body portion and an outer surrounding shell, both tapered in form and insertable one within the other, the wrapper shell comprising flexible sheet material having hooked projections at one end with corresponding slits in the other end of the wrapper to receive the projections with the ends of the sheet out of alignment and the ends of the sheet being moved into alignment after the projections are inserted, the slits having adjacent locking tongues parallel therewith and connected at one end only of the slit and longer than the width of the projection so that the end of the tongue will re-engage with the slit when the inner body portion is inserted in the outer shell in assembling the container.

RONALD I. DRAKE.
